UNITED STATES PATENT OFFICE.

CECIL HAMELIN TAYLOR, OF PHILADELPHIA, PENNSYLVANIA, ASSIGNOR,
BY MESNE ASSIGNMENTS, TO KNOX TAYLOR, OF HIGH BRIDGE, NEW
JERSEY.

AUTOMATIC GUN.

No. 823,004.

Specification of Letters Patent.

Patented June 12, 1906.

Application filed August 23, 1901. Serial No. 72,989.

To all whom it may concern:

Be it known that I, CECIL HAMELIN TAYLOR, a citizen of the United States, residing at Philadelphia, in the State of Pennsylvania, have invented certain new and useful Improvements in Automatic Guns, of which the following is a specification.

The annexed drawings and the following description set forth in detail one mechanical form embodying the invention, such detailed construction being but one of various mechanical forms in which the principle of the invention may be used.

In said drawings, Figure 1 represents a side elevation of the rear portion of the gun. Fig. 2 represents a side elevation of the remaining or front portion of the gun, the nozzle being shown in vertical section to illustrate the construction of the water-jacket. Fig. 3 represents a transverse longitudinal vertical section of the rear portion of the gun, showing the position of the breech-block in its rearmost position. Figs. 4, 5, and 6 represent transverse cross-sections of the gun on the lines 4 4, 5 5, and 6 6, respectively, of Fig. 1. Fig. 7 is a detail view representing a central longitudinal section of a portion of the gun, showing the cartridge-extractor at the instant a cartridge is being seized in the belt and a cartridge in the barrel is being fired. Figs. 8, 9, 10, and 11, respectively, represent detail views of the cartridge-extractor. Fig. 12 represents an end elevation of the frame or casing for the breech-block. Fig. 13 is a detail view illustrating means for manually reciprocating the breech-block.

The barrel A of the gun is rigidly secured to the frame B in any preferred manner and is provided with an outer and inclosing casing C. Preferably the barrel is also provided with a water-jacket D, extending the entire length thereof, which is likewise inclosed within the casing. The end of the water-jacket comprises an annular rib or flange, preferably formed integral with the barrel, to which one end of the outer cylinder d of the water-jacket is secured, the other end being secured to the frame, as at d'. The casing C is supported by the frame and from rings or bands c on the extension of the water-jacket.

The breech-block E of the gun is provided with a spindle F, that preferably is formed of a single piece therewith. The rear end of the breech-block is provided with a recess e, that

engages with and reciprocates over the cam-bolt G, secured to the frame of the gun, as by a bayonet-joint g, which permits the cam-bolt to be readily removed. The cam-bolt is held against rotation by screws g' and is provided on its surface with oppositely-arranged parallel grooves H, which are connected at their ends by cam-grooves h. Studs e', tapped or otherwise secured to the breech-block, take into these grooves, whereby both the breech-block and the spindle are forced to rotate when same engage the cam portion thereof. The forward end of the breech-block is movable in bearings f, provided in the frame, and has a flange f' formed integral therewith. A helical spring I is secured at one end to said flange and at its other end to a ratchet-wheel i, that engages with a corresponding ratchet-wheel i', secured to the frame. These ratchet-wheels are so constructed that when the spring is compressed the torsional tension of the spring in connection with the construction of the cam-grooves on the cam-bolt will cause the breech-block always to rotate in the same direction. It will be understood that while the spring I is being compressed it will also be put under torsional tension, which will be greater or less, according to whether the spring is prevented from expansion diametrically, and that as the rear end of the spring is held by the ratchet-wheels i and i' such torsional tension will be exerted in rotating the breech-block, to which the other end of the spring is attached. When the spring is expanding longitudinally and as it approaches the limit of its expansion, the ratchet-wheel i will jump from the ratchet-wheel i' and at the same time will advance slightly, so that at each compression of the spring the torsional tension thereof will be exerted in rotating the breech-block.

Secured to the spindle near its junction with the breech-block are two diametrically opposite wings or heads J, each forming a breech-face for co-operation with the cartridge substantially as a single breech-block, each provided on its side with longitudinal grooves j. Each head is also provided with a firing-pin K, arranged near the outer edge thereof and securely held in a counterbored recess k. An elongated cartridge-extractor L, comprising two side plates L', is secured to each of the heads by means of lugs l on the side plates, which engage in the grooves

The side plates are connected by a web l' , that is provided with a perforation l'' , that registers with the firing-pin. Each of the side pieces of the extractor is cut away, as at 5 l^3 , so as to form an outwardly-projecting spur l^4 , that engages with a pin l^5 in the spindle, whereby the outer end of the extractor is normally tilted forward upon the lugs l as a pivot and away from the firing- 10 pin. A pin l^6 on each head engages in slots l^7 , formed in the side pieces of the extractor, and limits the oscillation thereof. Said plates project slightly beyond the plane of the heads and are provided at their outer 15 edge with inwardly-projecting flanges l^8 , extending the full length of the extractor. These flanges are preferably notched or otherwise weakened, as at l^9 , to permit same to spring slightly apart and snap over the 20 rim of the cartridge when brought into engagement therewith.

The cartridges M are fed to the gun by means of a belt which passes around the spindle and is contained in a guideway m , that communicates with an inlet-opening m^1 and an outlet-opening m^2 , formed in the casing. The rims of the cartridges engage in a groove m^3 , which groove is arranged spirally, so that the rims of the cartridges shall project beyond the portion of the frame forming the guide when the cartridges are in position to be received by the cartridge-extractor. The forward portion of the spindle is provided with oppositely-arranged grooves f^2 , 30 which engage with the cartridges contained in the belt, and thereby feed the belt forward when the spindle is rotated.

After a cartridge has been withdrawn from the belt by the cartridge-extractor it is 40 fed to the barrel of the gun by means of a cartridge carrier or guide N , that is arranged to receive the cartridge when the breech-block is rotated. Said carrier or guide comprises, preferably, two approximately concentric 45 walls n and n' , which are spring-supported on the frame or casing of the gun. The inner wall n' is provided with a lip or projection n^3 , and one of the walls of each of the cartridge-grooves f^3 in the spindle is cut 50 away, so that said lip may project under the cartridge contained in said groove when the spindle is rotated and whereby the cartridge is guided into the carrier or guide. As the breech-block rotates the end of the cartridge 55 moves lengthwise of the extractor, so that when the breech-block has completed a half-turn the cartridge has been carried to the end of the extractor and opposite the firing-pin preparatory to being forced into the barrel 60 of the gun and being discharged. Since the cartridge carrier or guide is pivoted or otherwise secured to the gun so as to have a tilting or swinging movement, the lip portion of the carrier or guide, which engages with 65 the groove in the spindle and under the car-

tridge, may be forced outward when the spindle is rotated without interfering therewith. A cartridge-ejector is secured to the frame of the gun opposite the carrier or guide. Said ejector comprises an inwardly-projecting finger O , which is arranged adjacent to an opening o in the frame or casing and engages with the shell of the cartridge that has been discharged and pulls same from the extractor as said extractor is rotated and permits it 70 to drop through the opening.

In order to reciprocate the breech-block manually, a button or knob P is secured to the spindle and is movable in a slot Q , provided in the frame. The knob is affixed to 80 an arm r , secured to or formed integral with the sleeve R , mounted upon the spindle. The sleeve is held against movement lengthwise of the spindle by means of the flange f' , formed thereon, and a spring pawl or catch 85 r' , that is secured to the sleeve and engages in a groove f^4 in the spindle. By this arrangement the sleeve is caused to reciprocate with the spindle, but permits the spindle to rotate independently thereof and also permits the spindle to be readily disengaged and removed from the sleeve.

The portion of the casing inclosing the guide-bolt communicates, through a passage S , with openings or perforations s , provided in the handle or grip T . The trigger U is provided with a rearward extension u , that is bifurcated to engage with the grip and close said perforations when the trigger is in its locking position. The end of the breech-block fits snugly within this portion of the casing, so that an air-cushion is formed when the breech-block reciprocates. A buffer-spring V or other power-reservoir is placed either at the end of the guide-bolt or in the 105 recess in the breech-block to check and reverse the movement of the parts. The air or fluid cushion breaks the force of the rearward stroke of the breech-block and also decreases the initial velocity of the forward stroke 110 thereof. The regulation of the air-cushion by the control of the perforations s provides a means for regulating the reaction of the power-reservoir. In order to prevent accidental movement of the trigger, a safety W , comprising a lever w and an arm w' , adapted to engage with the trigger, is pivoted to the grip. The arm is normally held in engagement with the trigger by means of a spring X , arranged between same and the lever. The end of the trigger is recessed, as at U' , to receive the arm when the lever is compressed against the action of the spring, thereby permitting the trigger to be retracted.

In order to operate the gun, the breech-block is reciprocated manually until the cartridge-belt has been fed into position and one cartridge has been fired, after which the gun operates automatically, the breech-block being forced backward or "blown" back by the 120 125 130

force generated by the explosion of the cartridge and being returned to its forward position by the helical spring and the buffer-spring or air-cushion, or both. When the 5 breech-block reaches the limit of its forward stroke, the cartridge-extractor snaps over the rim of the cartridge which has been fed into position by the prior rotation of the spindle. This cartridge is withdrawn from 10 the belt when the breech-block makes its rearward stroke and rests in the groove in the spindle until the studs on the breech-block engage with the cam-grooves on the guide-bolt, when it is seized by the inwardly-projecting lip of the cartridge-carrier. The 15 rotation of the breech-block causes the cartridge to be fed downward toward the barrel of the gun and also to slide lengthwise of the cartridge-extractor toward its outer end and 20 radially with respect to the face of the breech-block to a position opposite the firing-pin. On the forward stroke of the breech-block the cartridge is forced into the barrel of the gun and the cartridge-extractor 25 is tilted on its pivot, so as to bring the firing-pin into engagement with the cartridge. Simultaneously a live cartridge is seized by the extractor and both the live cartridge and the shell of the exploded cartridge are with- 30 drawn, the one from the belt and the other from the cartridge-chamber, when the breech-block makes its return stroke. When the breech-block rotates, the live cartridge is fed downward, as described, and the shell of the 35 exploded cartridge is engaged by the ejector, which withdraws same from the end of the extractor. The rapidity with which the breech-block reciprocates is regulated by means of the air-cushion and the buffer- 40 spring. The resistance provided by the air-cushion is immediately controlled by the trigger, which in its forward or locking position completely closes the openings communicat- 45 ing with the air-chamber and which in its rearmost or retracted position uncovers these openings, so that practically no effect whatever is produced thereby. In this event the buffer-spring alone in connection with helical spring takes up the force of the 50 rearward stroke of the breech-block. Both the air-cushion and the buffer-spring serve to increase the initial velocity of the return stroke of the breech-block, whereby a more uniform speed of reciprocation is obtained. 55 The strain upon the studs that engage in the cam-grooves is partly relieved by the action of the spring, which tends to rotate the breech-block in the same direction as the cam moves when it is compressed.

60 By means of this construction I am enabled to provide an automatic gun that has a very small number of parts and that is extremely simple and accurate in its operation. Various changes may be made in the con- 65 struction herein set forth without departing

from the spirit of the invention provided the means set forth in the following claims be employed.

I claim as my invention—

1. In a gun, a movable breech-block having a plurality of breech-faces, means for reciprocating the same, and means for rotating the same in one direction to bring said breech-faces successively into line with the barrel, said last-named means comprising a cam-groove and a stud engaging therein. 75

2. In a gun, a movable breech-block having a plurality of breech-faces, means for rotating the same in one direction to bring said breech-faces successively into line with the barrel, and means for reciprocating the same, said last-named means comprising a helical spring. 80

3. In a gun, a movable breech-block having a plurality of breech-faces, means for reciprocating said block and for rotating it in one direction to bring said breech-faces successively into line with the barrel, and cartridge-feeding devices operated by the rotation of said block. 85

4. In a gun, the combination with a breech-block carrying cartridge-feeding spindle, of means for rotating and reciprocating said breech-block and spindle. 90

5. In a gun, the combination with a breech-block carrying a cartridge-feeding spindle, of means engaging the breech-block to rotate said breech-block and spindle, and means engaging the spindle to reciprocate said breech-block and spindle. 95

6. In a gun, a barrel, a breech-block, the one having movement relative to the other, a rotatable cartridge-feeding spindle operatively connected with the block, and means stationary with respect to the barrel and operatively connected with said block whereby the spindle is rotated through the relative movement of the barrel and block. 100

7. In a gun, a cartridge-guide, a rotating cartridge-feeder to feed the cartridges through the guide, one of the parts having longitudinal movement with respect to the other part, and devices stationary with respect to said guide and engaging the cartridge-feeder to effect rotation of said feeder through the relative longitudinal movement of said feeder. 110

8. In a gun, a cartridge-guide, a rotating cartridge-feeder to feed the cartridges through the guide, one of said parts having longitudinal movement with respect to the other part, and an extractor having a definite longitudinal relation to the cartridge-feeder and brought into operative relation with said guide through the relative longitudinal movement of the guide and cartridge-feeder. 120

9. In a gun having a guideway for the cartridges, a cartridge-feeding spindle rotating and reciprocating with respect to said guideway and an extractor carried with said spindle to engage the cartridge. 130

10. In a gun, a reciprocating and rotating breech-block, a helical spring resisting the longitudinal movement of the breech-block and means whereby the torsional tension of said spring due to longitudinal compression is utilized for rotating the block. 5
11. In a gun, a movable breech-block having a spindle formed integral therewith, means for reciprocating and rotating said breech-block, and means on said spindle engaging with a cartridge-belt to feed the same when the breech-block is rotated. 10
12. In a gun, a movable breech-block having a spindle formed integral therewith, 15 means for rotating and reciprocating said breech-block, means on said spindle engaging a cartridge-belt to feed same forward and a belt-guide formed in the frame of the gun and provided with a spirally-arranged groove 20 to receive the rims of the cartridges. 20
13. In a gun having a rotating breech-block, a cartridge-extractor carried with said breech-block to engage the cartridge and formed to permit lateral movement of the cartridge while held by the extractor, and means to feed the cartridge laterally said extractor also being movable toward and from said breech-block. 25
14. In a gun having a rotating breech-block with an eccentric breech-face, and a cartridge-extractor secured to the face of said breech-block to engage with the cartridges and feed the same laterally to the cartridge-chamber. 30
15. In a gun, a breech-block provided with an elongated cartridge-extractor pivoted to swing with relation to the block said extractor being constructed to engage the rim of the cartridge and permit movement of said cartridge lengthwise of the extractor across the 35 face of the breech-block. 40
16. In a gun, a cartridge-extractor formed to engage and retain the cartridge and pivoted to the breech-block to swing perpendicularly toward and from the face of the breech-block and means for normally holding one 45 end of said cartridge-extractor away from the face of the breech-block. 50
17. In a gun having a breech-face, a firing-pin stationary in the face of the breech-block and a cartridge-extractor formed to engage and retain the cartridge and having movement substantially perpendicular to the face of the breech-block. 55
18. In a gun, a breech-block provided with a stationary firing-pin, a cartridge-extractor formed to engage and retain the cartridge and pivoted to the breech-block, means normally holding the extractor away from said 60 firing-pin, and means for limiting the movement of said extractor. 65
19. In a gun, the combination with a rotating breech-block having an elongated cartridge-extractor secured thereto to engage the cartridge and permit movement of said 70 cartridge lengthwise thereof and radially with respect to the breech-block, of a guide secured to the frame of the gun and arranged to engage the cartridge and cause the same to move lengthwise of the extractor when the breech-block is rotated. 75
20. In a gun, the combination with a breech-block carrying a spindle provided with a groove to receive the cartridge, a cartridge-extractor secured to the breech-block 80 to engage the cartridge and hold the same in said groove and formed to permit lengthwise movement of the cartridge with respect to itself, and a guide secured to the frame of the gun provided with means to engage with the cartridge and move the same lengthwise of the extractor when the breech-block is rotated. 85
21. In a gun, the combination of a breech-block carrying a spindle provided with a recessed groove to receive the cartridge, a cartridge-extractor secured to said breech-block to engage with a cartridge and hold the same in the groove and formed to permit lengthwise movement of the cartridge with respect to itself, and a guide provided with an outwardly-projecting lip to engage in said recess and cause the cartridge to move lengthwise of the extractor and away from said groove when the breech-block is rotated. 90 95
22. In a gun, the combination with a rotatable breech-block, a stationary firing-pin in said breech-block, a cartridge-extractor pivoted to the breech-block so that the cartridge is normally held out of contact with the firing-pin, a cartridge-guide arranged adjacent to the breech-block to receive the cartridge held by the extractor when the breech-block is rotated and to guide said cartridge opposite the firing-pin, means for reciprocating the breech-block to engage the cartridges and to force the same into the cartridge-chamber and simultaneously oscillate the cartridge-extractor to bring the firing-pin into engagement with the cartridge. 100 105 110
23. In a gun, the combination with a breech-block having a cartridge-extractor secured thereto and movable therewith in a direction transverse to the axis of the breech-block and having substantially parallel fixed guides to engage the rim of a cartridge and permit the same to move in a direction transverse to the axis of the breech-block, of an ejector-finger arranged to project within the path of the extracted case held by said extractor and disengage the same from said extractor as the extractor is moved transversely. 115 120
24. In a gun, a part moved by the operation of the gun, firing mechanism, a trigger, a source of fluid-pressure coöperating with said part to control and cushion the movement thereof, and devices in operative relation with the trigger for regulating the action of the source of fluid-pressure and the speed of the moving part. 125 130

25. In a gun, a part moved by the operation of the gun, firing mechanism, a trigger, a source of power coöperating with the moving part and in which energy is stored by the movement of said part, and devices in operative relation with the trigger for regulating the action of said source of power and the speed of the moving part.
26. In a gun, the combination with the casing of a reciprocating breech-block engaging with the casing to form an air-chamber between same and the end of the breech-block, a passage communicating with said air-chamber and having an outlet in the grip of the gun, a trigger, and means on said trigger for regulating said outlet.
27. In a gun, the combination with a casing, a stationary guide-bolt secured to the casing, a reciprocating breech-block engaging with the casing to form an air-chamber between the same and the end of the breech-block, an outlet for the air-chamber, and a buffer-spring arranged between the guide-bolt and the breech-block to reverse the movement of the breech-block when said outlet is opened.
28. In a gun, the combination of a breech-block movable longitudinally and rotatable, an extractor carried by the breech-block and movable therewith, said extractor being formed to engage a cartridge and to permit lengthwise movement of the cartridge with respect to itself, and a relatively fixed cartridge-guide to engage the cartridge and move the same lengthwise of the extractor when the breech-block is rotated.
29. In a gun, a cartridge-extractor having guides to engage the rim of a cartridge and between which the cartridge is movable, said guides being relatively yielding in one part of their length to snap over the rim of a cartridge and relatively unyielding in another part to hold the cartridge rigidly.
30. In a breech-loading gun, a breech-bolt having a transversely-projecting cross-head, provided with a firing-pin in each of the arms thereof.
31. In a breech-loading gun, a breech-bolt having a transversely-projecting cross-head, and provided on the face thereof with opposite sections of a flangeway adapted to grasp the heads of cartridges.
32. In a breech-loading gun, a breech-bolt having a transversely-projecting cross-head carrying a firing-pin in each of the arms thereof and provided on its face with opposite sections of a flangeway adapted to grasp and to hold cartridges.
33. In a machine-gun, the combination of the reciprocating breech mechanism, firing mechanism operated solely by the breech mechanism, and a manually-operable controller to determine the operation of the said breech mechanism, substantially as specified.
- In testimony whereof I sign this application, in the presence of two witnesses, this 16th day of August, 1901.

CECIL HAMELIN TAYLOR.
